UNITED STATES PATENT OFFICE.

LOUIS BUCHALTER, OF NEW YORK, N. Y.

COMBINED COAT AND MUFFLER.

Application filed March 28, 1924. Serial No. 702,675.

To all whom it may concern:

Be it known that I, LOUIS BUCHALTER, a citizen of the United States, and a resident of the city of New York, borough of Manhattan, in the county and State of New York, have invented a new and Improved Combined Coat and Muffler, of which the following is a full, clear, and exact description.

10 This invention relates to wearing apparel and particularly to an improved combined coat and muffler and has for an object to provide a construction which will give the usual appearance both inside and out of an overcoat while presenting means which may be readily adjusted to act as a muffler.

Another object of the invention is to provide an overcoat in which the inturned front edge of the overcoat is so formed as to present means which will act as a muffler at 20 one time and act merely as a continuation of the inturned edge of the overcoat at another time.

In the accompanying drawing:—

25 Figure 1 is a perspective view of an overcoat embodying the invention, the same being shown on a figure and illustrating how the muffler section may be used.

Figure 2 is a view similar to Figure 1 but 30 with the coat removed from the figure.

Figure 3 is a fragmentary interior view of the upper part of the overcoat shown in Figure 2, the same being spread out and with the muffler sections in their folded or 35 inoperative position.

Figure 4 is a fragmentary side view of the overcoat shown in Figure 2, showing in dotted lines the location of part of the muffler.

40 Figure 5 is a fragmentary sectional view through Figure 4, approximately on line 5—5.

Referring to the accompanying drawing by numerals, 1 indicates a coat which may be an ordinary street coat or an overcoat as preferred, though usually the invention is applied to an overcoat. The coat 1 is of the usual structure except that the inturned edge 2 which is usually on overcoats, is preferably inturned an appreciable distance and extended upwardly toward the neck 3 further than usual where it is cut at the line 4 and the edges 5 and 6 hemmed or otherwise bound. Preferably, the edge 6 is turned in slightly and stitched down while the edge 5 is bound with some form of bind-

ing similar to the lining 7. By cutting the edge 2 along the line 4, a flap or muffler section 8 is produced which is preferably formed with a rounded recess or notch 9 and, consequently, with an upwardly extending restricted portion 10. As shown in Figure 3, a muffler section is arranged on each side of the overcoat so that the description of one will apply to both.

The rounded notch 9 and extension 10 are provided so that when the coat is in use and the muffler is pulled across the chest, these portions will cause the muffler to fit snugly around the neck as clearly indicated in Figure 1. If desired, a snap fastener or other securing means 11 may be provided on each of the muffler sections 8 to prevent independent movement thereof until desired. Also from Figure 5, it will be noted that the lining 7 extends to the line 12 and back to the inner edge of the section 8 so as to produce a finished appearance interiorly thereof in the same manner that the lining 7 produces a finished appearance to the interior of the coat. It will be noted that there is no extra piece stitched onto the coat but that the inturned edge 2 is extended upwardly further than usual in coats and severed along the line 4 to produce the desired muffler sections which are constructed to accomplish the desired purpose in the most efficient manner as just set forth.

When it is desired to use the overcoat without using the muffler, the same is left flatwise against the lining 7 as shown in Figures 3 and 4 where it merely acts as an extension of the inturned edge 2 and will not present an objectionable appearance nor will it present any objectionable thickness.

When it is desired to use the muffler, the overcoat is put on in the usual manner but before it is buttoned up the snap fasteners 11, if they are used, are unfastened and the muffler swung out to an outer position after which the coat is buttoned up and the muffler sections arranged substantially as shown in Figure 1. In the manufacture of my improved garment by making the muffler sections integral with the facings at the upper ends of the latter and making such extensions identical in form and size and laterally of a length less than the width of the lapel openings in the coat as will be understood from Figs. 1 and 3 of the drawing, I am able to economize in the lay-out and manufacture of the garments as com-

pared for instance to a garment wherein a muffler section might be formed on one fac-
ing of a sufficient lateral width or length to
close the entire lapel opening, to a consid-
erable extent.

What I claim is:

A coat having both of its inner front
facings provided at their edges remote from
the edges of the coat with integral exten-
sions at the upper ends of the facings, said
extensions being identical in form and size

and laterally of a length less than the width
of the lapel opening in the coat when closed
whereby both said facing extensions at the
upper ends of the facings may be combined 15
to form a muffler to close the lapel opening
of the coat when the coat is buttoned and
such extensions are adjusted for use as muf-
fler sections as and for the purposes set
forth.

LOUIS BUCHALTER.
